UNITED STATES PATENT OFFICE

GEORGE C. BEIDLER, OF ROCHESTER, NEW YORK

CAMERA BELLOWS SUPPORT

Application filed July 16, 1926. Serial No. 122,911.

This invention relates to apparatus for photographing books, writings and other objects, and has reference to so-called "commercial cameras" which are intended to contain a roll of film, the film from which is moved through an exposing chamber and cut into appropriate lengths, proportional to the area exposed within the chamber.

This invention relates to certain improvements which, in their general aspect, may be said to refer to novel lens board and bellows supporting instrumentalities for holding the lens and parts associated with it in operative relation to a copy board or copy holder, in such a manner as to provide clearance under the bellows and lens and between the lens and the copy holder in order that the copy may be manipulated expeditiously without liability of the operator encountering frames, hangers or the like, which are intended to support the lens board or the bellows.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a view in elevation of a photographing apparatus embodying the invention;

Figure 2 illustrates a view in front elevation thereof.

Figure 3 illustrates a view in elevation of a detail of a coupling.

In these drawings, 15 denotes a conventional type of base frame having two parallel rails 16 at the top on which wheels or sheaves 17 are rotatable. Standards 18 at the front of the frame are preferably constructed of tubular material applied to posts 19 on the clamps or couplings 20 that are secured to the rails at the front ends, and the standards are provided at their upper ends with T-couplings 21 that are rotatably applied to the standards. The stems of the T-

couplings are preferably split and provided with apertured ribs 22 at the edges of the split portions, to which apertures, fastenings are applied for clamping the stems of the couplings to the standards.

The sockets 23 of the couplings are also split and they have apertured ribs on each edge of the split sections, through which fastenings are inserted for clamping the arms 24 that extend into and project from the T-couplings. The arms extend forwardly and converge and preferably the forward ends of the arms have pivots 25 connected to them, the said pivots being carried by lugs 26 projecting from plates 27 that are attached to opposite edges of a lens board 28. In this apparatus the lens and a prism are employed, but as they are of well known types, they need not, it is thought, be described in detail.

A stirrup or hanger 29 has ends hooked as at 30 to engage the arms by which the stirrup is supported, and the said stirrup embraces a portion of the lower side of the bellows and prevents its sagging.

I claim:

In a photographing apparatus, a base frame having camera supporting rails, standards on said frame, arms extending approximately horizontally from the standards, a lens board supported by the said arms, and a bellows hanger suspended from the said arms and extending under the bellows.
